POWER UNIT FOR MACHINE TOOLS

Kurt O. Tech, Grosse Pointe Woods, Mich., assignor to
The Cross Company, Fraser, Mich., a corporation of
Michigan

Filed Aug. 20, 1965, Ser. No. 86,660

Term of patent 14 years

(Cl. D55—1)

FIG. 1 is a perspective view showing the front top and right side of a power unit for machine tools embodying the novel design of this invention.

FIG. 2 is a perspective view illustrating the rear top and left side thereof.

The dominant features of my design reside in the portions shown in full lines.

I claim:

The ornamental design for a power unit for machine tools, as shown and described.
